TRAVERSE MECHANISM

Giovanni Battista Calvi, Genoa-S. Quirico, Italy

Application May 3, 1948, Serial No. 24,804
In Italy May 10, 1947

4 Claims. (Cl. 242—158)

1

The present invention relates to a mechanical device for distributing and winding yarn on bottle bobbins or the like.

In the known devices meant for the same work, for the filling of the bobbins, the spoolers require a pawl provided with a thread guide which, sliding on the same thread of the bobbin, displaces itself gradually, while another device causes alternating motions to the thread guide and therefore provokes the formation of successive truncated cones of yarn on the bobbins. The result is that, owing to the unavoidable irregularity of the winding tension of the yarn fed to the bobbin, the working of said pawl is not always accurate and therefore an irregular winding of the yarn on the bobbin takes place.

Moreover, in the known types, there is a further drawback when winding very thin yarn, for instance silk, viz. it is necessary to keep a very low winding speed, because otherwise the yarn breaks.

Moreover, in the known types, in order to take into account the different winding diameter of the yarn during the successive rotations of the bottle bobbin, it is necessary to provide a continuously operative device by which, at every moment, the rotation speed of the bobbin is varied in order to keep constant the winding speed, in spite of the continuous variation of the diameter according to which the yarn is wound up. The necessity for the continuous operation of this device further necessitates a very low rotation speed of the bobbin.

The device, according to the invention, eliminates all these drawbacks and presents at the same time further advantages.

The mechanical device for distribution and winding of yarn according to the present invention is characterised by the fact that, in addition to known means for varying the speed transmitted between the motor and the principal member operated by it on the machine, there is provided a mobile equipment continuously displaced in the direction of the axis of the bobbin from its larger diameter to the smaller, a mechanism, provided with a thread-guide, carried by said mobile equipment, and with an alternating motion, in the same direction of motion as the mobile equipment, and mechanical means for giving to said mobile equipment and to said mechanism velocities exactly connected with each other and in precise and mathematical reciprocal relation, as well between themselves, as with the rotation speed of the winding bobbin.

The device is further characterised by the fact

2

that known means are provided in order to modify the ratio between the mobile equipment velocity and the rotation velocity of the bobbin.

The device is further characterised by the fact that known means are provided in order to modify the ratio between the velocity of the mechanism provided with the thread-guide and the displacement speed of the mobile equipment and therefore the rotation velocity of the bobbin.

10 The device is still further characterised by the fact that special means are provided for automatically stopping the motion of the mobile equipment, when it has reached the end of its active course, viz. when the bobbin has been completely filled, these means being also used, when this has taken place, to bring back the mobile equipment to the beginning of its active course for the winding up of a new bobbin.

In the annexed drawings there is illustrated, 20 by way of example, a preferred embodiment of the invention:

Figures 1 and 2 show external side views, at right angles to each other, of the machine provided with the device according to the invention; 25 Figure 3 shows a plan view of the machine, partly in full and partly in horizontal section along plane III—III of Figures 1 and 2; Fig. 4 shows a partial section along plane IV—IV of Fig. 3; Fig. 5 represents a schematical partial section along plane V—V of Fig. 3. Fig. 6 shows a schematical partial section along plane VI—VI of Fig. 3. Fig. 7 represents, on a larger scale, a partial schematical section along plane VII—VII of Fig. 3 and Figures from 8 to 12, show, still, on a larger scale, respectively a plan view in the direction of arrow VIII, the sections IX—IX, X—X, XI—XI and the view from below of section XII—XII of Fig. 7 for the group illustrated in that figure.

The main shaft 1 of the machine is operated 40 from motor 2 by means of pulleys 3 and 4 and a belt B. On shaft 1 are mounted, longitudinally slidable by means of keyways 5, the friction discs 6, one for each bobbin foreseen on the machine, and on the hub of disc 6, by means of ball-bearing 45 7, is mounted the end 8 of arm 9 ending in a cross-piece 10 toothed on top as a rack, which slides on a guiding surface 11 of the machine frame and engaging a toothed wheel 12 carried by shaft 13 connected to head 14 provided with a handle 15 which operates the successive positions, in axial direction, of friction disc 6, by means of the click device 16 and shell shaped disc 17. The friction disc 6 cooperates with another friction disc 18, mounted on shaft 19 of bobbin fore- 50 55 These details are repeated for each bobbin fore-

seen on the machine so that only the mechanism cooperating with one of the bobbins will be described.

On shaft 19 is mounted an helical gear 21 which engages helical gear 22 mounted on shaft 23. On one side of the latter is mounted pinion 24 engaging pinion 25 which operates shaft 26 at the end of which, inside a liftable lid 27 and by means of nut 28 is mounted the pinion 29. The latter engages pinion 30, also mounted, by means of nut 31, on shaft 32 which, at the other end, carries the helical gear 33 engaging helical gear 34 mounted on vertical shaft 35, the operation of which will be described later on. At the other end, shaft 23 carries the pinion 36 which by engaging pinion 37, operates shaft 38, which, by means of the helical gear 39 operates helical gear 40 mounted on shaft 41, the operation of which will be described later on.

Shafts 35 and 41 are parallel to each other and are supported by bearings fitted above and below on a fixed support 42 of the machine; shaft 35 has a threaded portion 43 and shaft 41 has a longitudinal groove 44; on said shafts is mounted a mobile equipment, particularly illustrated by Figures 7 and 12. Said mobile equipment consists of a tubular element 45 which, with the end sleeves 46 and 47, is slidably mounted on the external diameter of thread 43; at top and bottom ends of the tubular element 45 are mounted the hubs 48 of arms 49. Above top arm 49, freely rotatable on shaft 41, is mounted the cross-piece 50, which, urged by spring 51 carried by arm 49, has a tendency to rotate in the direction of arrow 52, so that the semicylindrical end 53 threaded on its internal surface engages thread 43 of shaft 35. By acting, at any moment, on extension 54 of cross-piece 50 in the direction of arrow 55, it will be possible to disengage, at will, the mobile equipment from the thread 43.

A pinion 56 is mounted on the lower arm 49 and by means of key 57 engages groove 44 of shaft 41 and is driven by it; pinion 56 engages pinion 58 mounted on shaft 59, supported for rotation by top and bottom arms 49 and having two threads 60 and 61 with opposed inclinations conveniently joined at the top and at the bottom in 62 and 63.

Inside said grooves is engaged the end of a prolonged button 65 introduced into the cylindrical cavity 66 of a rider 67 and kept therein by a setscrew 68. Button 65 is freely rotatable around its axis, inside cavity 66. The rider 67 is provided with the small rod 69 which passes at the exterior of tubular element 45 thus hindering the rotation of element 67; it is also provided with thread guide 70.

It must be observed that, on top, shaft 35 has a portion 71 of a diameter corresponding to that of the threaded bottom of screw 43. On an upright piece 72 of the machine is mounted by means of pivot 73 a rocking double lever 74, which, at one end is loaded with an adjustable weight 72 and, at the other end, carries a paraffin roller 76. Arm 74 can oscillate under the opposing effects of the yarn tension coming from element 77 and of weight 75; a spring element 78 hinders too large oscillations of the arm. The yarn will pass from paraffin roller 76 to thread guide 70.

The operation of the device is as follows:

The bobbins will rotate at an angular velocity depending on the gear ratio adopted for pulleys 3 and 4 used and depending also on the regula-

tion which will have been obtained by operating handle 15 and head 14.

Depending on the angular velocity of shaft 19 carrying the bobbin, it will be possible to obtain any angular velocity of rotation for the threaded shaft 35 by adopting a convenient ratio for the pair of interchangeable pinions 29, 30. Simultaneously grooved shaft 41 will rotate at a velocity which is a function of the rotation velocity of the bobbin-carrying shaft.

The rotation of the shaft 35 is such that the mobile equipment, through the engagement of the semicollar 53 with thread 43, displaces itself gradually, at a constant speed, in the direction of arrow 79. This motion will take place till the moment in which semicollar 53 arrives at the top portion 71 of shaft 35; then, the disengagement of the mobile equipment from shaft 35 will take place and the mobile equipment will stop. This will happen, when the whole bobbin will have been wound up.

At the same time, the rotation of shaft 41, through pinions 56 and 58 will cause the continuous rotation of shaft 59 and rider 67 will accomplish alternating motions by the cooperation of finger 64 and the double thread 60, 61; the amplitude of these alternating runs will correspond to the truncated cone portion of the bobbin.

During the winding up of a truncated cone 30 layer on the bobbin and in consideration of the fact that the bobbin rotates at a constant angular speed, the conditions of the winding up of the yarn are continuously variable; in spite of this, the winding up will take place in a perfect manner and under a regular tension of the yarn, because owing to the presence of the paraffin roller 76, the disposition, taken by the yarn, is continuously variable viz. it causes a continuous variation of frictional resistance of the yarn on 35 thread-guide 70, so that the portion of yarn going from thread-guide 70 to the bobbin is substantially submitted always to the same tension. This is due to the pendular oscillations made by arm 74 on pivot 73 and by the different direction of the thread-guide 70 in relation with the paraffin roller 76 during each alternate run of thread-guide 70.

From what has been said above it results that by the use of the device, according to the invention, a perfect homogeneity of winding up is attained, that the bobbin can rotate at a higher or lower speed according to the count of the yarn to be wound up, that the rotation speed of the bobbin controls also the motion speeds of the other parts of the device, that the lifting speed of the mobile equipment in the direction of arrow 79 can be adjusted in relation with the count of the yarn to wind up, by changing the pinions 29, 30 and lastly that, owing to the fact that by the elimination of all the causes which compelled to keep a very low speed when winding up coarse counts of yarn in the known devices, by the device according to the invention, it is possible to use very high winding speeds and, therefore, 55 to exploit at the utmost the production of the machine. Lastly, the motion of the thread-guide 70 being perfectly and mechanically operated, as well in the alternating runs, as in the general motion of the lifting of the mobile equipment, the winding will be done in the most perfect conceivable manner. Moreover the device is self disengaging when the bobbin is completely wound up.

Although, for descriptive reasons, the present invention is based on what has been described

and illustrated only by way of an example, many practical modifications can be made to the embodiment of the invention, all based, though, on the fundamental conceptions of the invention, covered in the following claims.

Having now particularly described and ascertained the nature of my said invention and in what manner the same is to be performed, I declare that what I claim is:

1. In a bobbin winder having an upright bobbin spindle, drive means and a variable speed transmission between the drive means and spindle, the provision of a yarn distributing device comprising two vertical shafts, gear means connecting each shaft for rotation with the bobbin at a speed which is a function of the speed of the bobbin, the first shaft being externally threaded and the second having a longitudinal groove, a yoke surrounding both shafts and having means releasably engaging the thread of the first shaft thereby to move the yoke longitudinally of the shafts, a vertical screw journaled in the yoke and having opposed intersecting threads with connecting ends, a first gear keyed to the screw, a second gear journaled in the yoke coaxially with the second shaft and engaging the first gear, a pin projecting radially inwardly from the second gear to engage in the longitudinal groove to rotate the second gear with the second shaft and

permit longitudinal movement of the yoke, and a thread guide mounted for longitudinal movement on the screw and including means holding said guide against rotation and means engaging in the threads of the screw.

2. A device as in claim 1 wherein the yoke comprises a tubular member surrounding the first shaft and having two arms extending therefrom, the screw being journaled between the two arms.

3. A device as in claim 1 wherein the gear means comprise replaceable gears for varying the speed of rotation of the shafts relatively to each other.

4. A device as in claim 1 including a variable friction drive mechanism for varying the speeds of the gear means relatively to the bobbin.
